UNITED STATES PATENT OFFICE

GEORGE P. KOCH, OF MARTINEZ, CALIFORNIA, ASSIGNOR TO SHELL OIL COMPANY, OF SAN FRANCISCO, CALIFORNIA, A CORPORATION OF CALIFORNIA

METHOD OF PRODUCING GASOLINE FROM CRACKED DISTILLATE

No Drawing.

Application filed March 29, 1926. Serial No. 98,364.

My invention relates to the refining of petroleum products and particularly to the refining of cracked distillates.

It is common practice to subject petroleum oils to heat and pressure for the purpose of changing their physical characteristics, this practice being known as "cracking", and the distillates resulting from the cracking operation being known as "cracked distillates".

10 The amount of such cracked distillate now produced is very large, such distillate being usually a gasoline or a distillate which can be redistilled to produce a large proportion of gasoline.

15 Cracked distillates, due to the process by which they are produced, contain considerable quantities of unsaturated hydrocarbons and often contain unstable compounds and sulfur compounds such as mercaptans, sulfides, disulfides and polysulfides. These compounds give a poor color and odor to the distillate as initially produced and both the color and odor get worse as the distillate stands. For the purpose of improving the color and odor and the keeping qualities of the final products, such as gasoline, produced from such cracked distillates, it is common practice to treat the distillate with various reagents. Unfortunately the chemical refining methods previously used, if effective in removing the undesirable compounds were defective in that they also removed a large part of the unsaturated hydrocarbons which were converted into sludge, 35 together with some of the other desirable portions of the oil. Since these unsaturated hydrocarbons form a very desirable component of gasoline designed to be used as motor fuel, it is highly desirable that they 40 be conserved.

It is an object of my invention to provide methods by which unstable and undesirable compounds may be removed from cracked distillates without unfavorably affecting the useful unsaturated hydrocarbons or the distillates themselves.

The objectionable compounds, including sulfur compounds, found in cracked distillates cannot be readily separated from the 50 useful saturated and unsaturated hydrocar-

bons by physical methods of refining like distillation or extraction with various solvents, for the reason that they have physical characteristics similar to those of the saturated and desirable unsaturated hydrocarbons in respect to boiling points and solubility in various liquids.

I have discovered that a good separation of the undesirable compounds from the valuable distillates and unsaturated hydrocarbons can be accomplished by treating a cracked distillate with nitric acid which, if the proper proportions are used, acts upon the undesirable compounds without materially affecting the valuable hydrocarbons. It is well known that nitric acid is a powerful oxidizing agent and it would be expected that its use in concentrated form would result in a marked action on substances like the unsaturated hydrocarbons which have a decided affinity for oxygen. I have found, however, that the nitric acid has apparently a marked preference for the undesirable compounds, particularly those containing sulfur, and when properly used, does not materially attack or affect the useful hydrocarbons. I appreciate that this is not only an unexpected result but one which is contrary to present accepted chemical practices and teaching, but I have practiced the invention on a large scale and the results given herein are those obtained in actual practice.

In using my invention I first treat the cracked distillate with concentrated nitric acid. I then wash the distillate with water; treat it with strong alkali such as sodium hydroxide or potassium hydroxide; again wash it with water; treat it with sulfuric acid; wash, neutralize with soda and again wash with water.

The treatment with alkali and sulfuric acid is that previously used in the art, for the refining of similar distillates except that since the nitric acid combines with the undesirable compounds, the amount of sulfuric acid to be used can be reduced considerably.

I find that in refining distillates containing about 1.0 per cent of sulfur, irrespective of the chemical combination in which the element may be, about 1.0 per cent of concen-

- trated nitric acid should be used, the proportion of nitric acid varying with the proportion of sulfur in the distillate to be treated. The sulfur in the distillate is originally in such a form that it distils over with the gasoline vapors. For example, in distilling gasoline from a cracked distillate containing about 1.0 per cent of sulfur as determined by quantitative analysis, I found that in the 50 per cent distilled off I obtained .87 per cent of sulfur. By subjecting the original cracked distillate to the above nitric acid treatment, I reduced the proportion of sulfur in the first 50 per cent of gasoline distilled to 0.11 per cent. 5
- The above mentioned original cracked distillate contained initially about 25 per cent of unsaturated hydrocarbons which, being quite volatile, form a most desirable component of gasoline. I found after treating such distillate for one hour with 1.0 per cent of concentrated nitric acid, that there was no reduction in the proportion of unsaturated hydrocarbons and practically no sludge formation. 10
- I found further, if the same distillate were treated as above described by alkali and acids with intermediate washings but entirely omitting the step of using nitric acid, that while some reduction in the sulfur content was observed, it was much less than where nitric acid was used, and that if the alkali and sulfuric acid treatments were carried to a point where the undesirable compounds were eliminated there was a considerable destruction of unsaturated hydrocarbons, a considerable formation of acid sludge, and considerable loss in value of product. 15
- The chemistry of the undesirable compounds is rather complex and having fully described above my method of operation, I prefer not to positively bind myself to any particular explanation of the theory of operation. I believe however that the nitric acid acts upon the sulfides, disulfides and polysulfides, and other sulfur compounds, oxidizing them and producing reaction products which, as they have a much higher boiling point than the distillate, can be separated therefrom by distillation; or reaction products which being water soluble are washed out by the washing treatment; or perhaps reaction products which yield readily to the later alkali or acid treatment to form substances which are readily separable from the distillate. 20
- I claim as my invention:
1. A method of separating undesirable sulfur compounds from distillates consisting of substantially only the gasoline fractions of petroleum oils containing unsaturated hydrocarbons, which comprises: initially determining by analysis the quantitative measure of the sulfur in the distillate to be treated; treating said oils in liquid phase with concentrated nitric acid in equal proportion by weight to that of the sulfur content of the distillate, irrespective of the form of combination of the element, without materially affecting the unsaturated hydrocarbons; and thereafter removing the reaction products formed by the union of said nitric acid with said compound. 25
  2. A method of separating undesirable sulfur compounds from cracked distillates consisting substantially of gasoline fractions containing unsaturated hydrocarbons, which comprises: determining the proportion of the sulfur in the distillate to be treated; treating said oils in liquid phase with concentrated nitric acid in equal proportion by weight to that of the sulfur content of the distillate, irrespective of the form of combination of the element, without materially affecting the unsaturated hydrocarbons; and thereafter washing the oil with water, alkali and acid to remove the reaction products formed by the union of said nitric acid with said compounds. 30
  3. A method of separating undesirable sulfur compounds from distillates consisting of substantially only the gasoline fractions of petroleum oils containing unsaturated hydrocarbons, which comprises: treating said oils in liquid phase with nitric acid in substantially equal proportion by weight to that of the sulfur to be removed, irrespective of the form of combination of the element, without materially affecting the unsaturated hydrocarbons; and thereafter removing the reaction products formed by the union of said nitric acid with said compounds. 35
  4. A method of separating undesirable sulfur compounds from distillates consisting of substantially only the gasoline fractions of petroleum oils containing unsaturated hydrocarbons, which comprises: treating said oils in liquid phase with nitric acid in substantially equal proportion by weight to that of the sulfur to be removed, irrespective of the form of combination of the element, without materially affecting the unsaturated hydrocarbons; and thereafter distilling off the oil and unsaturated hydrocarbons from the reaction products formed by the union of said nitric acid with said compounds. 40
  5. A method of separating undesirable sulfur compounds from distillates consisting of substantially only the gasoline fractions of petroleum oils containing unsaturated hydrocarbons, which comprises: treating said oils in liquid phase with nitric acid in substantially equal proportion by weight to that of the sulfur to be removed, irrespective of the form of combination of the element, without materially affecting the unsaturated hydrocarbons; and thereafter washing the oil with water to remove the reaction products formed by the union of said nitric acid with said compounds. 45
  6. A method of separating undesirable sulfur compounds from distillates consisting of substantially only the gasoline fractions of petroleum oils containing unsaturated hydrocarbons, which comprises: treating said oils in liquid phase with nitric acid in substantially equal proportion by weight to that of the sulfur to be removed, irrespective of the form of combination of the element, without materially affecting the unsaturated hydrocarbons; and thereafter removing the reaction products formed by the union of said nitric acid with said compounds. 50

substantially only the gasoline fractions of petroleum oils containing unsaturated hydrocarbons, which comprises: treating said oils in liquid phase with nitric acid in substantially equal proportion by weight to that of the sulfur to be removed, irrespective of the form of combination of the element, without materially affecting the unsaturated hydrocarbons; and thereafter washing the oil with water, alkali and acid to remove the reaction products formed by the union of said nitric acid with said compounds.

7. A method of producing a gasoline of good color and odor from a cracked distillate containing objectionable sulfur compounds and desirable unsaturated hydrocarbons, which comprises: treating the cracked distillate in liquid phase with nitric acid in an amount substantially equal by weight to the amount of sulfur to be removed, irrespective of the form of combination of the element, without materially affecting the unsaturated hydrocarbons and thereafter distilling off gasoline containing the unsaturated hydrocarbons from said distillates.

8. A method of producing a gasoline of good color and odor from a cracked distillate containing objectionable sulfur compounds and desirable unsaturated hydrocarbons, which comprises: treating the cracked distillate in liquid phase with concentrated nitric acid in an amount substantially equal by weight to the amount of the sulfur content of the oil, irrespective of the form of combination of the element, without materially affecting the unsaturated hydrocarbons; washing the distillate with water to remove a portion of the reaction products formed by the union of said nitric acid with said compounds; and thereafter distilling off gasoline and unsaturated hydrocarbons from said distillates.

9. A method of producing a gasoline of good color and odor from a cracked distillate containing objectionable sulfur compounds and desirable unsaturated hydrocarbons, which comprises: treating the cracked distillate in liquid phase with concentrated nitric acid in an amount substantially equal by weight to the amount of the sulfur content of the oil, irrespective of the form of combination of the element, without materially affecting the unsaturated hydrocarbons; subjecting the above treated distillate to further alkali and acid action and washing; and thereafter distilling off gasoline and unsaturated hydrocarbons from said distillates.

10. A method of producing a gasoline of good color and odor from a cracked distillate containing objectionable sulfur compounds and desirable unsaturated hydrocarbons, which comprises: treating the cracked distillate in liquid phase with concentrated nitric acid in an amount substantially equal by weight to the amount of the sulfur content

of the oil, irrespective of the form of combination of the element, without materially affecting the unsaturated hydrocarbons; washing the distillate with water to remove a portion of the reaction products formed by the union of said nitric acid with said compounds; subjecting the distillate to further alkali and acid action and washing and thereafter distilling off gasoline and unsaturated hydrocarbons from said distillates.

In testimony whereof, I have hereunto set my hand at Martinez, California, this 12 day of March, 1926.
